(57) **CLAIM**

The ornamental design for a mouthpiece for use in intraoral phototherapies, as shown and described.

DESCRIPTION

FIG. 1 is a top perspective view of a mouthpiece for use in intraoral phototherapies according to the design.

FIG. 2 is a bottom perspective view of the mouthpiece for use in intraoral phototherapies according to the design.

FIG. 3 is a top view of the mouthpiece for use in intraoral phototherapies according to the design.

FIG. 4 is a bottom view of the mouthpiece for use in intraoral phototherapies according to the design.

FIG. 5 is a right side view of the mouthpiece for use in intraoral phototherapies according to the design.

FIG. 6 is a left side view of the mouthpiece for use in intraoral phototherapies according to the design.

FIG. 7 is a front view of the mouthpiece for use in intraoral phototherapies according to the design; and,

FIG. 8 is a back view of the mouthpiece for use in intraoral phototherapies according to the design.

The broken lines shown herein are for illustrative purposes only and form no part of the claimed design.

The broken lines depict portions of the mouthpiece for use in intraoral phototherapies that form no part of the claimed design.
